United States Patent Office.

WILLIAM H. WILLSON, OF NEW YORK, N. Y.

Letters Patent No. 82,465, dated September 22, 1868.

IMPROVED HAND-BRUSHING AND POLISHING-APPARATUS.

The Schedule referred to in these Letters Patent and making part of the same.

TO ALL WHOM IT MAY CONCERN:

Be it known that I, WILLIAM H. WILLSON, of the city, county, and State of New York, have invented certain new and useful Improvements in Hand-Brushing and Polishing-Apparatus; and I do hereby declare that the following is a full, clear, and exact description of the same, reference being had to the accompanying drawings, making a portion of this specification, in which—

Figure 1 is a longitudinal section of an apparatus made according to my invention.

Figure 2 is a transverse section of the same, taken in the line x x of fig. 1.

Figure 3 is a transverse section of the same, taken in the line y y of fig. 1.

Figure 4 is a transverse section of the same, taken in the line z z of fig. 1.

Similar letters of reference indicate corresponding parts in all the figures.

This invention consists in a coiled spring and a system of gearing arranged within the cylindrical body of a rotary brushing and polishing-device, furnished with suitable axial handles, in such manner as to produce the requisite rotatory movement of the same, the object being to provide a rotary apparatus for the purposes indicated, which may be operated by hand, thereby dispensing with power as ordinarily applied to this class of devices.

The invention further consists in so arranging a friction-brake within the cylindrical body just named that the rotatory movement of the latter may be readily stopped when desired.

The invention further consists in a novel combination of parts, whereby the efficient operation of the apparatus, and the convenience with which it may be handled or manipulated, is materially increased.

To enable others to understand the construction and operation of my invention, I will proceed to describe it with reference to the drawings.

A represents a frame, composed of two circular disks, a b , and an end bar, c , these parts being connected by suitable braces, a' , working in bearings provided in the disk b and bar c .

In the axial line of the cylindrical body B, hereinafter described, is a stem, C, this stem being provided, at its outer end, with a handle, A*.

Between the bar c and disk b is a coiled spring, D, shown in fig. 1, and also indicated in red outline in fig. 4. The inner end of this spring is attached to the stem C, and the outer extremity thereof is connected with one of the braces a' , of the frame A, in such a way that the uncoiling of the spring will rotate the stem C just mentioned with reference to such frame.

The stem C has attached thereto a ratchet-wheel, d , and placed loosely thereon is a spur-gear, e , furnished at one side with a spring-pawl, b' , working with or into the ratchet-wheel d in such manner that during the uncoiling of the spring the spur-gear e will be turned with the stem C, but in the coiling of the spring the pawl will slip over the ratchet-wheel, thereby enabling the apparatus to be wound up for use.

The spur-gear e gears into a pinion, f , upon a shaft, c' , which extends from one of the disks a b to the other, and is provided with a spur-wheel, g , which, acting through a pinion, h , spur-wheel i' , and pinion j , rotates a shaft, e' , upon the extremity of which, at the inner side of the disk b , is a friction-pinion, m , which is placed in contact with the inner edge of an internal cylindrical shell, E, which is secured upon an axial shaft, E', furnished at its outer end with a handle, B*, and having its inner end screwed firmly into the centre of the disk b of the frame A.

Secured externally upon the shell E is the cylindrical body B of the apparatus, the shell just mentioned being formed, in the first instance, separately from the body, merely for the sake of convenience in construction, and constituting, in fact, a portion of the body itself.

The exterior of the body B, when the apparatus is to be used for brushing purposes, is provided with radial bristles, as represented in red outline in figs. 1 and 4, but when designed for polishing purposes, the surface of such body is coated with emery, or equivalent abrading-material.

The springs D, having been coiled by turning the handle A* of the stem C in the requisite direction, operates, when unwinding or uncoiling, through the stem C and the system of gears hereinbefore described, to rotate the friction-pinion m , which, in its turn, communicates a rotatory movement to the body B, the body being

held or sustained by the handle B* in suitable contact or proximity with the article to be brushed or polished, as the case may be, the other handle, A*, that of the stem C, being left loose or only slightly supported by the hand of the person using the apparatus, so that it may be free to turn in the operation of the latter, as just hereinbefore described.

In order that the apparatus may, when required, be retained with its spring in a coiled or wound-up condition, and that its movement may be stopped with facility when desired, a brake, consisting of a semicircular spring, I, is secured, at its middle, to a plate, C*, fixed upon the shaft F, at the inner end of the handle B* thereof, the end portions of such brake, when the latter is expanded, being pressed against the interior of the shell E, or, in other words, of the body B, with sufficient force to neutralize that exerted by the coiled spring D, which operates to rotate such body, thereby stopping the movement of the latter.

Extending from one end portion of the spring or brake I to the other, is a chain or strap, r, the centre of which is attached to the inner end of a lever, u, passing through the plate C*, with its opposite end situated in such relation with the handle B* that it may be conveniently pressed toward the same to draw upon the chain or strap just mentioned, so as to bring the end portions of the brake inward away from the internal surface of the shell E, thereby permitting the rotation, as hereinbefore set forth, of the body B, of which such shell forms a part, it being only necessary to release the lever in order to permit the brake to operate to stop the motion of the body B, as just mentioned.

What I claim as my invention, and desire to secure by Letters Patent, is—

1. So arranging the coiled spring and the system of gearing within the cylindrical body furnished with axial handles, as to secure the rotatory movement of such body, substantially as herein set forth.
2. The arrangement of the friction-brake within the cylindrical body furnished with axial handles, whereby the rotatory movement of the same may be stopped, substantially as herein set forth.
3. The arrangement of the coiled spring, the system of gearing, the stem of the handle A*, and the frame A, with reference to each other and the friction-pinion m, dividing the cylindrical body B, substantially as and for the purpose specified.

WM. H. WILLSON.
